UNITED STATES PATENT OFFICE

WOLF KRITCHEVSKY AND HAROLD C. PRUTSMAN, OF CHICAGO, ILLINOIS, ASSIGNEES
TO RIT PRODUCTS CORPORATION, OF CHICAGO, ILLINOIS, A CORPORATION OF DELA-
WARE

DYE REMOVER

No Drawing.

Application filed April 30, 1930. Serial No. 448,783.

Our invention relates to a composition of matter intended for use as a color remover or stripper for dyed fabrics.

Due to the extensive practice of this art, 5 both commercially and in households, there is a large and growing demand for a product that will accomplish the desired result in a satisfactory manner. The class of chemicals most generally used for this purpose is that 10 known as sulphites, hydrosulphites and sul- phoxylates. A most commonly used compo- sition consists of a mixture of zinc dust and sodium bisulphite which, in a water solution, evolves hydrogen and forms a chemical 15 known as zinc hydrosulphite. A well known chemical of this class is sodium hydrosulphite of the general formula $\text{Na}_2\text{S}_2\text{O}_4$, known com- mercially in this country as lykopon, bleacan, decrolin, etc. This chemical when boiled in 20 water either alone or in the presence of an alkali or acid evolves hydrogen according to the equation:

25 This substance is sold in large quantities for stripping dyes and for reducing vat dyes in dyeing and tinting. The chemical is quite efficient, but is very unstable due to its capacity of absorbing oxygen and moisture from 30 the air, resulting in liberation of hydrogen. It is therefore necessary that the product be sold in sealed containers and that it be used promptly by the purchaser.

35 Many attempts have been made to obviate this difficulty and to stabilize the substance. In one instance the sodium hydrosulphite is combined with formaldehyde resulting in the formation of sodium hydrosulphite formaldehyde, otherwise known as sodium sul- 40 phoxylate. This product is somewhat more stable than hydrosulphite alone but is not stable in a practical sense.

45 Another method of effecting stabilization is to form normal zinc salts known as zinc hydrosulphites or protoline or zinc sulphonylate hydrosulphite. These represent an improvement over lycopon but it is not stable and must be isolated from air and moisture.

50 In view of the fact that all of the substances heretofore mentioned are water soluble, it

has been proposed that a desired result might be secured by forming the insoluble derivatives, and zinc salts, known as basic zinc sulphonylate hydrosulphite has been developed, otherwise known as "rongalite" or "formopon-extra". The substances are considerably more stable in air, due to the fact that they are insoluble in water. However, in order to use them they must be combined in an acid solution to neutralize the zinc salt and liberate the free acid. The result is a compound much weaker than straight sodium hydrosulphite. However, even these derivatives are not stable for indefinite periods in 60 open air.

65 In order to merchandise a package product for household use it is difficult, if not impossible to provide hermetic sealing. For that reason, we have for some years marketed a product under Patent No. 1,524,737 con- 70 sisting of a mixture of a hydrosulphite and a solid acid-reacting substance. This product is an improvement over the art, but still not entirely satisfactory. It is for this reason 75 that we have carried on a series of experiments looking toward the development of a stripping substance that could be marketed in package form and that would be stable under all atmospheric conditions.

80 As the result of our experiments, we have found that the main reason for the decom- position of the hydrosulphite compounds was that the substance is hygroscopic and de- 85 composes in the presence of air and moisture. We have, therefore, determined that if the hydrosulphite particles are enveloped in a water-proof or water-resistant film, the oxy- 90 gen of the air, and moisture will be excluded and the substance will remain stable in- definitely.

95 In speaking of hydrosulphites, we include under that name all compounds that belong to this class. It may include the salts of hydro-sulfurous acid of the general formula

100 It also may include the different salts of the condensation product hydro-sulfurous

acid, or its salts with formaldehyde which have the following formula

5 known as formaldehyde sulfoxalic acid and its salts whether sodium, zinc, calcium, etc. and formaldehyde bisulfuric acid and its salts, the formula being

10 mixtures thereof. These compounds are technically known as lykopon, which is sodium hydrosulphite, decrolin or protolin, 15 which is zinc hydrosulphite-sulphoxylate, or formopon which is sodium sulfoxalate formaldehyde or basic zinc sulfoxalate formaldehyde technically known as formopon extra, rongalite, etc.

20 There are many other formulæ and many other technical names but for brevity the substances are herein called hydrosulphites, as they belong generally to the hydrosulphite class, the hypothetical hydrosulfurous acid 25 being the parent substance of the whole class.

We have found that when sodium hydrosulphite or one of the derivatives heretofore mentioned is intimately mixed with an oily substance, the product will remain stable even 30 when it is exposed to the air for practically an indefinite period. An oily substance that will accomplish this result may be a hydrocarbon such as petroleum, kerosene, or paraffine, or a metallic soap that is insoluble in 35 water, such as aluminum stearate or even an ordinary anhydrous soap, such as sodium stearate, or a sulphonated soap or a vegetable oil, or a fatty acid like oleic acid, stearic acid, sulphonated fatty acid or a naphthenic acid 40 or a sulphonated petroleum residue.

We have determined that when a quantity of any of the mentioned oily substances in excess of 2½% of the total amount of hydrosulphite, depending on the character of the 45 oily substance, is intimately mixed therewith, an oily film is formed around each particle of the hydrosulphite thus providing an enclosing envelope that serves to exclude air and moisture for practically an indefinite 50 period.

A product such as described can be used in that form in operations where an aqueous solution is not necessary. However, where a water solution is required it will be found 55 desirable to first supply to the water an agent that will serve to act on the oily substance, and release it from its intimate association with the hydrosulphite unless the oily substance itself is soluble or disperses in 60 an excess of water. This will permit the hydrosulphite to enter into solution and to act in the expected manner.

An agent that will act as required may consist of a substance such as an alkali like 65 caustic soda, caustic potash, soda ash, borax,

dry sodium phosphate, or ammonia, or derivatives that are suitable to form a soluble soap with a free fatty acid or an oil.

In the use of this agent the oily substance is freed from the hydrosulphite and permitted to enter into solution or suspension. 70 In the use of the saponifying agent, particularly where an excess of alkali is used, there will be formed an alkaline solution that will assist in the stripping action. 75

However, in order that the product may be merchandised in packages for household use it is desirable that an agent be combined with the treated hydrosulphite having the capacity for reacting with or acting upon 80 the oily substance only when the mixture is placed in an excess of water. The agent may have the capacity of saponifying the oily substance and causing it to form a soap in which case the oily substance is detached from the hydrosulphite and the hydrosulphite is permitted to enter into solution. 85

An essential of the mixture is that an agent shall be selected that will be dormant or inactive relative to the sulphite and its oily envelope so long as the compound remains in 90 dry mixture.

To illustrate, a compound contemplated in the last named disclosure may consist of 90 grams of sodium hydrosulphite and 10 grams of oleic acid, sulpholeic acid, castor oil, corn oil, sulphonated castor oil, stearic acid etc. 95 These are first intimately mixed so that substantially every particle of the hydrosulphite receives a coating or envelope of the oily material. Such a compound is useful without the addition of other substances when used in a non-aqueous solvent. However, it has been found to be advantageous to combine in solid 100 mixture soda ash, anhydrous borax or ammonium carbonate in sufficient proportions to saponify the oil; or in a less proportion, in which case part of the oil may be saponified, thus forming a quantity of soap that will 105 emulsify the remainder of the oil. Or we 110 may prefer to utilize a substantially larger quantity of the saponifying agent, that is, more than sufficient to saponify the oil, in which case we provide an excess of alkali in 115 the bath which will assist the hydrosulphite reaction.

In the compound last described, it may occur under extreme climatic conditions that there will be a limited reaction of the solid substance before the compound is added to a bath but this will result merely in the formation of a small quantity of soap which will act to emulsify the oily substance. Even though all the oily substance became saponified, the so-formed soap would envelop the hydrosulphite and prevent the deterioration of the active ingredient. Soap is water-resistant to a small amount of water, although soluble in an excess of water. This compound, either in a solid mixture or in solution 120 125 130

will accomplish the purpose of providing an effective stripper that may be sold in packages or otherwise without deterioration.

5 We may prefer to also add to the solid compound other substances such as solvents, assistants, penetrators, and fillers, so long as any such added substance does not interfere with the function of the oily substance.

10 We have not attempted to specify or mention all possible substances that may be used or that will function to protect the hydrosulphite from deterioration, depending on the disclosures as made to describe the principle of the invention.

15 We claim:

1. A composition of matter consisting of a substantially dry mixture of a stripping chemical of the hydrosulfite class, a saponifiable oily substance that will encase the individual particles of the stripping chemical and tend to exclude air and moisture therefrom, and an alkaline reacting chemical that will in a water solution saponify said substance and release the said substance from its intimate contact with said stripping chemical and permit said stripping chemical to enter into waste solution.

20 2. A composition of matter consisting of a hydrosulphite, a saponifiable substance capable of enveloping the particles of hydrosulphite with a film that will exclude air and moisture, and a quantity of an alkaline reacting substance which in a water solution is capable of saponifying a portion of the film-forming substance.

25 3. A composition of matter consisting of a hydrosulphite, a saponifiable substance capable of enveloping the particles of hydrosulphite with a film that will exclude air and moisture, and a quantity of an alkaline reacting substance which in a water solution is capable of saponifying the film-forming substance and provide the bath with an excess of alkali.

30 4. A composition of matter consisting of a solid mixture of hydrosulphite, a saponifiable oil that will envelop the particles of the hydrosulphite and exclude air and moisture, and soda ash.

35 5. A composition of matter consisting of sodium hydrosulphite, sulphonated castor oil and soda ash.

In testimony whereof we have affixed our signatures.

WOLF KRITCHEVSKY.
HAROLD C. PRUTSMAN.
